RADIANT HEATING PAD FOR THE FEET
AND LOWER LIMBS

Bert P. McCann, Seattle, Wash.

Application May 1, 1950, Serial No. 159,181

4 Claims. (Cl. 219—19)

1

This present invention consists of a pad of a size convenient for resting the feet on or standing upon and which is so arranged that it is an effective radiant heating means for the feet and lower legs. The invention makes use of an insulated electrical resistance wire element which is of such resistance and length that it can never attain, from normal electric outlets, a temperature that will be uncomfortable to rest the feet on. Means are further provided for directing the greater amount of the heat generated upwardly in the form of radiant energy so that the feet can be maintained at a comfortable temperature and the radiant transmission from the surface of the pad will be sufficient to keep the calves of the legs and knees warm at the same time.

In the past, the normal means for heating dwellings, offices, factories, and the like, was by heating the ambient air and to circulate this either by conversion from radiators or by induced draft, such as is normally considered forced air circulation. Such heating is generally accepted but there are so many instances in which it does not provide warmth for the feet of those who are forced by their vocations to sit or stand at some particular point of work. This is often true of people working at desks and the like. In most forms of industry a person is required to sit or stand at some one position and is not able to move about, consequently, his feet, which are within the lower strata or the coldest of the ambient air, quite often suffer from cold and this generally results in an over-all cold feeling on the part of the person. Radiant energy heating wherein steam or hot water pipes are laid in the floors of factories, office buildings and homes, provide a very fine solution of this problem. However, they can only be available to a relatively small proportion of the people, and it is to provide this type of heat to those persons who work or live in areas where such heating cannot be made available that I have developed this present foot heating pad.

This invention provides an individual heating pad of firm, durable material which can be walked on or stood on, or upon which the feet can be rested and which, while intended to cover only a relatively small area, will provide a high degree of comfort and improved good health to a large mass of working people. For instance, the man operating a machine tool, which normally is on a concrete floor, can have on top of the concrete floor a pad just sufficiently large to take care of his essential movement, and this pad can be heated very economically and the heat given out by it will counteract the cold floors, warm his feet, and the radiant energy given off from the upper surface of the pad will

warm the lower legs so the person will be comfortable and thus able to achieve his highest possible work output. There are many other persons such as those who stand watch in commercial establishments as officers of the law, or on sea-going vessels, who thus, for the first time, have available to them, a source of real foot comfort.

The principal object of this invention is to provide a heating pad that will provide a warm floor area for a person confined to a limited area.

A further object of this invention is to provide an electric heating pad which may be used out-of-doors or in manufacturing establishments and the like, where the same must be capable of taking unusual use without damage to itself or endangering the person using the pad.

A further object of this invention is to provide an electric heating pad making use of low temperature heating wire to the end that expensive thermostatic controls, and the like, with their attendant servicing difficulties, will be eliminated.

A further object of this invention is to provide an electric heating pad in which the entire surface of the pad will form a transmitting surface for radiant energy at low temperature levels so they will give real warmth to the user yet will never be hot enough to be uncomfortable when the feet are kept in close engagement therewith, as by standing thereon for long periods.

A further object of this invention is to provide a low temperature electric heating pad that can be economically constructed and which will have a long, trouble-free useful life.

Further objects, advantages and capabilities will be apparent from the description and disclosure in the drawings, or may be comprehended or are inherent in the device.

In the drawings:

Figure 1 is a perspective view showing how this heating pad may be used by a desk worker;

Figure 2 is a perspective view, partly broken away and shown in section, and with a portion of the heating wire raised from its retaining groove to more fully illustrate the construction thereof;

Figure 3 is an enlarged perspective view taken in the same sense as Figure 2 and showing the channels for the electric heating elements and the manner in which the terminal connector is imbedded in the heating pad so that no unexpected strain on the exposed cord can disrupt the heating unit itself;

Figure 4 is a top plan view of an electric heating pad based on the teachings of this present invention and showing the form that has been found best adaptable for outdoor use in that the pad will not accumulate water on its surface;

Figure 5 is a cross-sectional view taken along the lines 5—5 of Figure 4 with the same broken away in the center and foreshortened;

Figure 6 is an enlarged perspective view of one corner of the pad of Figure 4 illustrating the construction thereof;

Figure 7 is a fragmentary vertical sectional view showing an alternate insulating arrangement;

Figure 8 is a fragmentary vertical sectional view showing an alternate use of reflective insulation material.

Referring more particularly to the disclosure in the drawings, the numerals 10 and 11 designate respectively the upper and lower layers which form the heating pad 12 of this invention. These two layers may be made of any dense nonconductive material that may be made in sheet form or molded. The basic requirement is that the sheet be relatively stiff so there will be no tendency for the edges to curl, yet they should preferably be slightly flexible when joined together so that they will conform to the floor surface on which they are used even though the same is not perfectly level and smooth. It is further necessary that this material be of sufficient density so that it can either be water-proofed or preferably will be inherently water-proof. The materials that have been found most suitable are the tempered hard wall-boards. The layers may, however, be molded of quite a wide range of materials such as plastic, rubber, or the synthetic rubbers. The laminated materials which combine rubber and fabric, plastic and fabric, or flexible sheet stock, such as paper and the like, are also suitable. It is desirable that the material from which the layers are made have some dielectric properties and that they be resistant to the entrance of moisture.

Disposed between the top and bottom layers is the insulated low temperature heating cable 14. Cables of this order have been used for heating under special conditions for some time. They were originally developed for use in heating hot-beds and greenhouses and have found some use in the radiant heating, particularly of small homes where they are quite often tacked to the lath and then covered with plaster. Such cables are designed for the type of electric current available and are so arranged, due to the wire gauge and to their length, that the resistance is such that the temperature of the cable can never rise above the designed maximum. As the cable deteriorates after years of use, the maximum temperature may not be achieved but there is no danger of it ever going above the designed maximum. This is a very important characteristic of this type of heating cable in that it permits the use of an economical heat source which is not dependent upon the use of thermostatic control. However, it is conceivable that the smaller type of screw-adjusted thermostat might be used in an installation of this order, in the interest of over-all economy of construction and in the interest of not introducing into the unit an electrical device that might need service or replacement. It has been found preferable to carefully design the cable to keep it below the maximum allowable temperature. The exact cable design will be dependent, to a degree, upon the materials from which the top and bottom layers are made and the thickness of the same, together with the effectiveness of insulation if used. Practice has determined that there should never be any point in a surface that the feet are to contact which

should exceed 35° Fahrenheit, and for use, as under a desk, where the user's feet may rest at the same point for a considerable period, this temperature should not exceed 80° Fahrenheit.

Cable 14 should normally be placed in grooves as 16 cut into, preferably, the bottom layer. This leaves the top layer of uniform strength throughout its entirety and adds materially to its longer life, and further tends to more thoroughly equalize the distribution of heat throughout the top layer. The usual form of groove 16 is indicated in dotted lines in Figure 2, it being necessary to start at the cable connector and anchor 18 and make a continuous panel coil which then must have its outermost end connected to the cable connector 18.

As the prime need of a foot-warming pad of this order is for use for many kinds of floors, it may not only be unheated, but actually may be in contact with the ground, as for instance, a concrete ground floor, and thus have its heat conducted away from it so that it is much colder than the ambient air. Under such conditions, it naturally follows, it is believed, that steps should be taken to prevent the dissipation of the heat downwardly and endeavor to retain the maximum floor radiation upwardly. To this end it is found desirable to employ one of the various accepted forms of insulating material. One very effective means is to employ a sheet of reflective insulating material 17 between the top and bottom layers. This keeps the thickness of the heating pad to a minimum and does not affect its ability to flex slightly. The reflective material normally used is aluminum foil and will readily permit sufficient deformation to partially encircle the lower part of wire 14 as it rests in grooves 16. An improved theoretical use of the foil or sheet aluminum is shown in Figure 8 in which the foil or sheet rests in a recess in layer 11 and the top layer is supported by a grid of support ribs 19. This arrangement permits the maximum reflection from the upper surface of the sheet. An alternate construction is shown in Figure 7 in which a fibrous sheet is employed, such as 20, between the top and bottom layers. In this construction it is found best to form insulating fibre sheet 20 preferably as part of the bottom layer so that again, the top layer may be a sheet of uniform thickness. In this form it is deemed desirable to form grooves within fibre sheet 20 for the accommodation of the insulated heating wire 14. In this modified form it has been found most effective to employ rivets or through-bolts as 22 which will be set slightly inwardly of the surface of the top and bottom layers. This makes it possible to obtain a good seal at the juncture 24 so that the heating cable can be protected, as well as the fibrous board, from the intrusion of moisture.

Normally, it has been found comparatively easy to bond the upper and lower layers together, either by heat fusion, or by the application of adhesives suitable for the surfaces joined together. There is, however, no real objection to the employment of through-rivets or flush bolting through the body of the pad if that appears necessary because of the type of sheets used in the two layers.

In Figure 2 the preferred form of this foot-heating pad is shown as adapted to the use of those persons who are well shielded from the weather or dampness. However, it has been found that many persons who must work under adverse weather conditions, are actually the ones

who are urgently in need of a device of this order, and to serve this field, there has been illustrated in Figures 4 and 5, a modified form of structure, modified only however, in that the pad is pierced with a large number of regularly positioned openings 30 so as to reduce the surface and to prevent the accumulation of water thereon by allowing it to drain off. In other words, a form of screening or open mat is provided which has been found most adaptable for the outside use. The various openings 30 are, of course, so disposed as to be in between the loops of cable 14 so that the structure, basically, is the same as shown in Figure 2. The cross-sectional view of Figure 5 shows generally the structure where the top and bottom layers are fused together, as can be achieved with many of the plastics and certain of the rubber substitutes.

It is readily apparent that a pad of this order will be very simple to use. Normally, the wattage employed is relatively low and the temperature, of course, will vary somewhat with the conditions of use. For inside use it normally will not exceed 100 or 200 watts, and for outside use will rarely exceed 300 watts, due to the fact that the pads need to cover only 3 or 4 square feet. The pad functions in use very similarly to a radiantly heated floor. In other words, the entire upper, or top layer, becomes heated to the maximum allowable temperature, normally 80° Fahrenheit, and the top surface then becomes a heat transmitter. The heat transfer, of course, follows the same laws as any other form of heating and takes fully into account the natural tendency of warm air to rise. This causes a conduction transfer which may amount to as much as 45% of the total heat transmitted and leave for radiant transfer approximately 55% of the total. It will thus be apparent, it is believed, that not only will the soles of the feet be warm, but a good deal of heat will be passed on to the lower limbs.

It is believed that it will be clearly apparent from the above description and the disclosure in the drawings that the invention comprehends a novel construction of a radiant heating pad for the feet and lower limbs.

Having thus disclosed the invention, I claim:

1. A radiant heating pad for the feet and lower limbs, comprising: a top layer and a bottom layer of durable sheet material having dielectric and water resistant properties, said top and bottom layer being fixedly secured together; an insulated, low temperature heating cable coiled between said layers to produce a temperature on the upper surface of said top layer within a range of temperatures comfortable to feet, resting on the pad, said cable having a single wire of such small gauge and being of such length that it cannot heat beyond a low designed maximum temperature; said bottom layer being configured to accept said heating cable to lie in a plane below said top layer; a cable connector positioned between said top layer and bottom layer and both ends of said cable being connected to said connector making a continuous panel coil; and a sheet of heat-reflective, metal foil on the upper surface of said bottom layer and pressed into the configurations in said bottom layer to lie below said heating cable.

2. A radiant heating pad for the feet and lower limbs, comprising: a top layer and a bottom layer of durable sheet material having dielectric and water resistant properties; an insulated, low temperature heating cable coiled between said layers and lying in a common plane below the lower surface of said top layer to produce a temperature on

the upper surface of said top layer within a range of temperatures comfortable to feet, resting on the pad, said cable having a single wire of such small gauge and being of such length that it cannot heat beyond a low designed maximum temperature; said cable having means for connecting the cable to a source of electricity; insulating material disposed between said layers and below said heating cable only; said bottom layer being configured to accept said heating cable and said insulating material.

3. A radiant heating pad for the feet and lower limbs, comprising: a durable thin heating pad of a size to accommodate the feet of a person; a low temperature heating cable coiled in said heating pad and lying in a common horizontal plane to produce a substantially even temperature on the upper surface of the heating pad within a range of temperatures comfortable to feet, resting on the pad, said cable having a single wire of such small gauge and being of such length that it cannot heat beyond a low designed maximum temperature; said cable having a dielectric coating insulating said cable to prevent conduction of electricity from said cable to the surfaces of said pad; said cable having means for connecting the cable to a source of electricity; and said pad having a single sheet of reflective insulating material positioned under said cable to reflect heat from said cable upward.

4. A radiant heating pad for the feet and lower limbs, comprising: a durable flat, thin heating pad of a size to accommodate the feet of a person, said pad having separate upper and lower members with their exterior faces forming the top and bottom surfaces of said pad; a low temperature heating cable coiled in said heating pad below the lower surface of said upper member to produce a substantially even temperature on the upper surface of the heating pad within a range of temperatures comfortable to feet, resting on the pad, said cable having a single wire of such small gauge and being of such length that it cannot heat beyond a low designed maximum temperature; said cable having a dielectric coating insulating said cable to prevent conduction of electricity from said cable to the surfaces of said pad; said cable having means at the juncture of its two ends for connecting the cable to a source of electricity; and a single sheet of heat insulating material disposed between said cable and said lower member.
